[57] CLAIM

The ornamental design for a beverage container, as shown and described.

DESCRIPTION

FIG. 1 is a top front right perspective view of a beverage dispenser showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken line showing of a liquid beverage and a cup in FIG. 1 is for illustrative purposes only and forms no part of the claimed design.
